(57) **CLAIM**

The ornamental design for a mop head, as shown and described.

DESCRIPTION

FIG. 1 is a top perspective view of a mop head showing my new design;

FIG. 2 is a bottom perspective view thereof;

FIG. 3 is a front elevation view thereof, the rear being identical thereto;

FIG. 4 is a bottom plan view thereof;

FIG. 5 is a top plan view thereof; and,

FIG. 6 is an end elevation view thereof the opposite end being identical thereto.

The beading on the bottom of the mop head is partially shown for ease of illustration and is understood to repeat uniformly throughout that surface.
